UNITED STATES PATENT OFFICE.

CHARLES F. PFALZGRAF, OF BALTIMORE, MARYLAND, ASSIGNOR TO BALTIMORE STAMPING & ENAMELING CO., OF BALTIMORE, MARYLAND, A CORPORATION OF MARYLAND.

HOUSEHOLD SIFTER.

Application filed April 17, 1928. Serial No. 270,641.

This invention relates to improvements in household sifters and has for its object to provide an improved construction of agitator crank-bar on which the agitator may be 5 mounted in a way to be rotated thereby without having direct connection therewith, and to also mount the crank-bar in the shell of the sifter in an exceedingly simple and cheap manner.

10 With these main objects in view, the invention is illustrated in the accompanying drawing, wherein,—

Fig. 1 shows a vertical longitudinal section through the sifter,—the section being 15 taken on the line 1—1 of Fig. 2.

Fig. 2 illustrates the sifter-shell partly in side view with a fragment of the same broken away and shows the agitator and crank-bar in vertical cross-section, and

20 Fig. 3 shows an enlarged perspective detail of a portion of the agitator and a portion of the crank-bar on which the same is mounted.

Referring to the drawing, the numeral 5 designates the cylindric shell of the sifter 25 which in this instance is shown with the usual ornamental and circumferential stiffening beads 6, and which also has an annular circumferential fold 7 in which the screening wire 8 is secured to hold it in place on the 30 interior of the shell.

The screen 8 is of the usual concavo-convex form so that an agitator may be revolved over the concave upper side thereof to work the flour or other material through the screen.

35 At diametrically opposite sides the shell 5 is provided with bearing openings 9 and 10 which are located in the same horizontal plane and above the screen in which the crank-bar 11 is to be mounted, as will now be 40 explained.

The crank-bar 11 is formed of a single piece of spring wire of sufficient stiffness to serve its purpose and has a short straight and horizontal bearing-end 12; a bowed intermediate 45 portion 13; an intermediate short horizontal bearing portion 14 and a crank-end 15.

The short bearing-end 12 projects through and has bearing in the opening 9 in one side of the shell-wall while the intermediate bearing portion 14 extends through the opening 50 10 in the opposite side of the shell wall and has bearing therein.

It will be noted that a shoulder 16 is formed between the straight end 12 and the bowed portion 13 of the crank-bar and that 55 a similar shoulder 17 is formed between the bearing-portion 14 and the said bowed portion. The utility of these shoulders 16 and 17 will presently be explained.

The agitator is formed of a series of arched bars 18 each of which has a head 19 at each of its ends and all of the heads at one side of the agitator are brought into register and clipped together by tangs 20 of one head engaging the others.

60 These registered and clipped-together heads 19 of the agitators have bearing-openings 21 therethrough.

65 It will further be noted that each agitator bar has a bend therein near one of its end heads which produces an inwardly-projecting shoulder 22 and these shoulders project inwardly far enough to extend across the path of the bowed portion 13 of the crank-bar adjacent to the shoulders 16 and 17 thereof. These shoulders 16 and 17 are utilized in my structure to effect a rotation of the agitator from the bowed portion of the crank-bar regardless whether the crank be turned 70 in one direction or the other.

75 The two horizontal bearing-ports 12 and 14 of the crank-bar serve to carry the heads 19 of the agitator, while the shoulders 16 and 17 thereof keep the agitator-bars 18 spread and arched.

80 The intermediate bowed portion 13 of the crank-bar, because of its tendency to spread the bearing-ports 12 and 14 apart keeps the end 12 of the bar in its bearing opening 9 of the shell and thus eliminates all necessity 85 for nuts or other means on the outer end 12 of the bar to keep the latter from withdrawing from its bearing.

Moreover, it will be seen that as the crank-bar is free of all obstruction, other than the 90 several bends therein, it may readily be threaded through the bearing opening 10 at one side of the shell; then through the openings 21 in the heads at one side of the agitator; then sprung and passed through the heads at the opposite side of the agitator and entered in the bearing-opening 9 in the opposite side of the shell,—the springing of the 95 bar because of its bowed-portion 13 enabling 100

the operation of insertion or removal to be readily effected, and all because of the cheap and simple construction of said crank-bar.

A handle 23 of conventional form is shown attached to the shell.

Having described my invention, I claim,—

1. In a sifter, the combination with a cylindric shell of a semi-cylindric screen sustained in said shell, a crank-bar having horizontal bearing portions mounted in opposite walls of the shell said crank-bar being bowed between the said bearing-positions, an agitator mounted on the horizontal bearing portions of said crank-bar at opposite sides of said bowed portion thereof and means for turning the agitator from the bowed portion of the crank-shaft.

2. In a sifter, the combination with a cylindric shell of a screen sustained in said shell, an agitator in the shell with spaced bearing-openings therein, a crank-bar extending through the shell-wall and having a horizontal bearing portion which bears in said shell-

wall and which extends through one of the bearing-openings of the agitator said crank-bar being also provided with a bowed portion and a bearing-end beyond said bowed portion said latter end being sprung into position to pass through the other bearing-opening of the agitator and also through an opening at the opposite side of the shell.

3. In a sifter, the combination with a cylindric shell of a semi-cylindric screen in said shell, a crank-bar having two horizontal bearing portions and a bowed portion between the two bearing portions, an agitator having a plurality of arms the opposite ends of which are mounted on the two bearing-positions of the crank-bar at the outer sides of the bowed portion thereof and shoulders formed on an arm of the agitator to project in the path of the bowed portion of the crank-bar whereby to drive the agitator.

In testimony whereof I affix my signature.

CHARLES F. PFALZGRAF.
